UNITED STATES PATENT OFFICE.

MARGARET COLLINS, OF BOSTON, MASSACHUSETTS.

NURSERY-TOILET.

1,358,933.

Specification of Letters Patent. Patented Nov. 16, 1920.

Application filed October 3, 1919. Serial No. 328,149.

To all whom it may concern:

Be it known that I, MARGARET COLLINS, a subject of the King of Great Britain, and resident of Boston, in the county of Suffolk 5 and State of Massachusetts, have invented new and useful Improvements in Nursery-Toilets, of which the following is a specification.

This invention relates to a chamber-vessel 10 and chair support, and particularly to a vessel and chair especially adapted for use in the nursery.

I have found from practical experience in the care of children extending over a period 15 of several years that the ordinary chamber-vessel is poorly adapted for use by very small children and especially by small boys, as they invariably soil the floor, or if the vessel is used beneath a chamber-vessel, they 20 soil the seat of the chair by directing the urine over the edge of the vessel. I am aware that bed pans have been designed with baffles for the purpose of obviating the spilling of urine over their edges, but they have 25 not been suitable for use as chamber-vessels by children as the baffles have been of such form that a child could not be placed upon one of these vessels astride the baffle without great discomfort and danger of injury to the 30 legs of the child. Furthermore such vessels cannot be used with the usual form of child's chamber-chair as no provision has been made in the seat of the chair for the upward projection therethrough of the baffle.

35 A principal object of my invention is to provide a chamber-vessel, which is so designed as to be especially adapted for use by male children to prevent the direction of urine over the forward edge of the vessel, 40 the baffle being so arranged that a child may be placed upon the vessel astride the baffle without discomfort to the child.

A still further object of the invention is to 45 provide a chamber-chair with which my improved vessel is especially adapted to coöperate, the chair being so constructed that the vessel may be supported beneath the seat of the chair with the baffle projecting upwardly through the opening in the seat adjacent to 50 the forward edge of the chair.

A still further object of the invention is to provide an improved nursery toilet of sanitary, simple and inexpensive construction.

The invention will now be described in 55 connection with one specific embodiment of

the genus of my invention. In the accompanying drawings:—

Figure 1 is a perspective view of my improved chamber-vessel;

Fig. 2 is a rear elevation of the vessel; 60

Fig. 3 is a side view of a child's chamber chair with which my improved vessel is adapted to be used;

Fig. 4 is a plan view of the chair taken on line 4—4 of Fig. 3; 65

Fig. 5 is a side view of the chair, the back being omitted for clearness and a portion of the side of the chair being omitted to show the manner in which the vessel is held beneath the seat of the chair; and 70

Fig. 6 is a rear view of the chair, the back being omitted, showing the vessel in position beneath the seat of the chair.

Referring to the drawings in detail, the numeral 1 designates a vessel constructed in 75 accordance with the present invention. This vessel may be constructed of any suitable material, for example, china, porcelain, enameled ware, hard rubber, or the like, and of such size and proportions as is best suited 80 for use by very young children. The vessel comprises a body 2, which is provided at its upper edge with a flange 3 formed integrally therewith. Preferably formed integrally with the flange 3 is a handle 4. Arranged 85 diametrically opposite the handle 4 and made integral with the body 2 is a relatively high and narrow baffle 5. The upper end of the baffle projects a suitable distance above the flange of the vessel to stop and prevent 90 any urine which may be directed upwardly against it from going over the edge of the vessel. For this purpose the edges 6 of the baffle are also directed forwardly so that the 95 baffle is substantially hood or scoop-shaped.

As is apparent from Fig. 2 the baffle 5 is 100 comparatively narrow so that the child may be placed upon the vessel astride the baffle with no discomfort and without such a spreading of the child's legs as would from frequent use of the vessel tend to permanently bow or otherwise disfigure the legs of the child.

A child's chamber-vessel is customarily 105 employed with a chair beneath which the vessel is disposed. In Figs. 3 to 6 I have disclosed such a chair especially adapted for use with the chamber hereinbefore described. This chair comprises a seat portion 7 suitably supported upon a base 8 of reed, 110

wicker or other suitable material, open at the rear as shown in Fig. 6, and a back 9 of reed or other suitable material.

The seat 7 is provided with an opening 10 of substantially the same diameter as the inside of the vessel 1, the opening 10 being extended as at 11 toward the front edge 12 of the seat sufficiently to receive the baffle portion 5 of the vessel when the vessel is disposed beneath the seat 7. It is particularly desirable that the child may sit in the chair in a position such that its legs may extend over the forward edge of the chair in a natural manner, and therefore the forward edge of the extended portion 11 of the opening 10 is formed as close as possible to the forward edge of the seat. The seat 7 is provided with a sanitary pneumatic or other cushion 13 adjacent the edge of the opening 10, although if desired this may be omitted.

Hinged to the edge 12 of the seat by hinges 14 is a cover member 15 which when the chair is to be used with a vessel may be folded down into the position shown in Fig. 3, and which may be folded back over the seat 7 to cover the opening 10 when it is desired to use the chair as an ordinary child's chair. Stops or bumpers 16 of rubber or other suitable material may if desired be attached to the under side of the cover 15 to support the cover from the seat 7 when the cover is folded back.

For supporting the vessel 1 beneath the seat 7 in alinement with the opening 10, spring wire guides 17 are attached to the under side of the seat on either side of the opening 10, which are adapted to engage beneath the flange 3 of the vessel as most clearly shown in Fig. 6, and which firmly press the flanged edge of the vessel against the under side of the seat. These guides are not extended rearwardly as far as the opening 10 in order to permit the upward insertion through the opening 10 of the baffle portion 5 of the vessel. With the cover 15 in the position shown in Fig. 3, to position the vessel beneath the chair, the portion 5 of the vessel is first inserted upwardly through the opening 10 adjacent the rear portion of the opening until the upper edge of the flange 3 of the vessel engages the under surface of the seat 7. The vessel is then pushed forwardly between the guides 17 with the flange 3 engaged between the horizontal portions of the guides and the under surfaces of the seat, until the baffle portion 5 is positioned in the extension 11 of the opening 10. The vessel will then be properly alined beneath the opening 10 and held firmly in position.

I claim:

1. A nursery toilet comprising in combination a chair having an opening in the seat thereof, and a vessel provided with an

upwardly extending baffle portion, said 65 opening being so formed as to permit the positioning of the vessel beneath the seat of said chair with said baffle portion extending upwardly therethrough.

2. A nursery toilet comprising in combination a chair having an opening in the seat thereof, and a vessel provided with a narrow upwardly extending baffle portion, said opening being so formed as to permit the positioning of the vessel beneath the seat 75 of said chair with the baffle portion immediately adjacent the forward edge of the chair seat and extending upwardly therethrough.

3. A nursery toilet comprising in combination a chair having an opening in the 80 seat thereof, and a vessel comprising a body portion, a narrow scoop-shaped baffle portion extending upwardly above the upper edge of said body portion and an outwardly extending marginal flange integral with the 85 marginal edge of said body portion, said opening being so formed as to permit the positioning of the vessel beneath the seat of said chair with its marginal flange in contact with the under surface of said seat and 90 with its baffle portion immediately adjacent the forward edge of said seat and extending upwardly therethrough.

4. A nursery toilet comprising in combination a chair having an opening in the 95 seat thereof, and a vessel comprising a body portion, a narrow scoop-shaped baffle portion extending upwardly above the upper edge of said body portion and an outwardly extending marginal flange integral with the 100 marginal edge of said body portion, and means attached to the under side of said chair seat and engaging beneath the flange of said vessel for positioning said vessel beneath said seat in alinement with the opening therein with the baffle portion of said vessel extending upwardly through said opening.

5. A nursery toilet comprising in combination a chair having an opening in the 116 seat thereof, and a vessel comprising a body portion, a narrow scoop-shaped baffle portion extending upwardly above the upper edge of said body portion and an outwardly extending marginal flange integral with the 115 marginal edge of said body portion, and spring guides attached to the under side of said chair seat and engaging beneath the flange of said vessel for positioning said vessel beneath said seat in alinement with the opening therein with the baffle portion of said vessel extending upwardly through said opening.

6. A nursery toilet comprising in combination a chair comprising a seat having an 125 opening therein, an air cushion on said seat surrounding said opening, and a cover hinged to the forward edge of said seat, and

a vessel comprising a body portion, a baffle portion extending upwardly above the upper edge of said body portion and an outwardly extending marginal flange integral with the marginal edge of said chair seat and engaging beneath the flange of said vessel for positioning said vessel beneath the

said seat in alignment with the opening therein with the baffle portion of said vessel extending upwardly through said opening. ¹⁰

Signed by me at Boston, Massachusetts, this twenty-seventh day of September, 1919.

MARGARET COLLINS.
